JAR HOLDER

Peter Stellingwerf, Orange City, Iowa

Application June 18, 1938, Serial No. 214,543

3 Claims. (Cl. 81—3.2)

The present invention relates to new and useful improvements in jar holders and has for one of its important objects to provide, in a manner as hereinafter set forth, a device of this character which is adapted to firmly secure different sizes of jars to facilitate screwing a cap thereon or removing said cap therefrom.

Another very important object of the invention is to provide, in a jar holder of the type including a flexible jaw, novel means for expeditiously tightening said flexible jaw on the jar and for securing said flexible jaw in gripping position.

Other objects of the invention are to provide a jar holder of the character described which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings, wherein like characters of reference designate corresponding parts throughout the several views, and wherein:

25 Figure 1 is a view in front elevation of an embodiment of the invention, showing a jar mounted in the device.

Figure 2 is a view principally in horizontal section through the invention, taken substantially on the line 2—2 of Fig. 1, the jar being omitted.

30 Figure 3 is a fragmentary view in vertical section, taken substantially on the line 3—3 of Fig. 1.

Figure 4 is a view in side elevation of the device.

35 Figure 5 is a detail view in perspective of the holder through the medium of which the device is removably mounted on a wall or other support.

Figure 6 is a detail view in perspective of the clamping rod.

40 Figure 7 is a fragmentary view in horizontal section, taken substantially on the line 7—7 of Fig. 4.

Figure 8 is a perspective view of the bracket.

45 Figure 9 is a cross sectional view, taken substantially on the line 9—9 of Fig. 2.

Figure 10 is a top plan view of a modification, portions thereof being shown in horizontal section.

50 Referring now to the drawings in detail, it will be seen that the embodiment of the invention which has been illustrated comprises a metallic bracket which is designated generally by the reference numeral 1. The bracket 1 is formed to provide an arcuate stationary jaw 2 having integral legs 3 and 4 on the ends thereof. The leg 55 3 is formed to provide a bottle opener 5 (see

Fig. 4). The leg 4 includes an angular portion 6 adjacent the stationary jaw 2. The legs 3 and 4 terminate in outturned feet 7.

The bracket 1 further includes a substantially V-shaped metallic brace 8 which is secured at 9 to the stationary jaw 2. On its ends the brace 8 terminates in outturned feet 10 which are secured to the feet 7. The feet 7 and 10 of the bracket 1 are engageable in a metallic holder 11 which is adapted to be mounted on a wall or other suitable support. It will be observed that the holder 11 is of such construction that the bracket 1 may be readily removed therefrom.

The reference numeral 12 designates a flexible jaw in the form of a resilient metallic strap having one end fixed to the leg 3 of the bracket 1. Adjustably mounted on the free end portion of the jaw 12 is an extension 13. The extension 13 has formed therein a circumferential slot 14 in which a bolt 15 which is mounted in the free end portion of the jaw 12 is operable. A wing nut 16 is provided on the bolt 15 for clamping the extension 13 in adjusted position on the flexible jaw 12. The elements 2, 12 and 13 have mounted thereon a lining 17 of suitable material, preferably rubber.

At its free end, the extension 13 terminates in a housing or the like 18 for a metallic block 19. The reference numeral 20 designates a clamping rod which is rotatably mounted in the block 19. Cotter pins 21 secure the rod 20 against longitudinal movement in the block 19. At one end, the rod 20 terminates in a right angularly extending operating handle 22. The other end portion of the rod 20 extends slidably through openings 30 which are provided therefor in the angular portion 6 of the leg 4 and the brace 8 of the bracket 1. This end portion of the rod 20 is provided on one side with ratchet teeth 23. A resilient metallic pawl 24 on the adjacent end portion of the stationary jaw 2 is engageable with the teeth 23 for releasably securing the rod 20 in adjusted position. A cotter pin 25 prevents withdrawal of the rod 20 from the bracket 1.

It is thought that the operation of the device 45 will be readily apparent from a consideration of the foregoing. With the resilient jaw 12 in expanded or open position, a jar 26 is inserted therein, as shown to advantage in Fig. 1 of the drawings. Then, with the ratchet teeth 23 on the rod 20 facing the pawl 24 said rod is pushed inwardly in the bracket 1, carrying with it the free end of the flexible jaw 12, thus clamping said jaw firmly around the jar. Of course, the jar 26 bears against the stationary jaw 2. The 50 55

flexible jaw 12 is secured in clamping position on the jar by the pawl 24 engaged with the ratchet teeth 23. When it is desired to open the flexible jaw 12 for releasing the jar, this may be expediently accomplished by simply rotating the rod 20 in a manner to disengage the ratchet teeth 23 from the pawl 24 thereby allowing said rod 20 to slide outwardly in the bracket 1. The extension 13 on the flexible jaw 12 may be expediently adjusted to accommodate different sizes of jars by simply loosening the wing nut 16 on the bolt 15. Split rivets 27 secure the rubber linings 17 to the elements 2, 12 and 13. The device is also adapted to clamp a conventional cap in a manner to permit a jar to be screwed thereto or removed therefrom.

In the modification shown in Fig. 10 of the drawings, the reference numeral 28 designates an extension having one end portion secured, as at 29, to the end portion of the main strap 12 which is connected to the leg 3 of the bracket 1. The extension 28, it will be observed, extends adjacent the portion 2 of the bracket 3 and conforms substantially to the curvature thereof and has its other end portion secured to the portion 6 of said bracket 1, as at 30. Then, the inner end portion of the lining 17 which is on the strap 12 is secured to the extension 28. In other respects the modification shown in Fig. 10 of the drawings is substantially similar structurally to the embodiment shown in Figs. 1 to 9, inclusive, of said drawings.

It is believed that the many advantages of a jar holder constructed in accordance with the present invention will be readily understood and although preferred embodiments of the device are as illustrated and described, it is to be understood that further modifications and changes in the details of construction may be resorted to which will fall within the scope of the invention as claimed.

What is claimed is:

1. A jar holder comprising a supporting bracket adapted to be mounted on a support and including a stationary jaw, a flexible jaw having one end connected to said stationary jaw and

cooperable therewith for gripping a jar, a rod rotatably connected to the free end portion of the flexible jaw and extending rotatably and slidably into the bracket, and coacting means on said rod and said bracket for releasably securing the flexible jaw in gripping position, said means including ratchet teeth on the rod, and a pawl on the bracket engageable with said teeth.

2. A jar holder comprising a bracket adapted to be mounted on a support, said bracket including a stationary jaw, a flexible jaw having one end secured to said stationary jaw, said flexible jaw being cooperable with the stationary jaw for clamping a jar, an extension adjustably mounted on the free end portion of the flexible jaw, a rod rotatably and slidably mounted in the bracket and rotatably connected to the free end portion of the extension for clamping the flexible jaw on the jar, said rod including a series of ratchet teeth, and a pawl mounted on the bracket and engageable with the teeth for releasably securing the flexible jaw in clamping position.

3. A jar holder comprising a bracket including an arcuate stationary jaw, legs on the ends of the stationary jaw, one of said legs including an angular portion adjacent the stationary jaw, outturned feet on the ends of the legs, a substantially V-shaped brace connected to the stationary jaw at an intermediate point and including outturned feet secured to the first named feet, said feet providing means for mounting the bracket on a support, a flexible jaw having one end secured to the stationary jaw, an extension adjustably mounted on the free end portion of the flexible jaw, said flexible jaw being cooperable with the stationary jaw for gripping a jar, a block on the free end portion of the extension, a manually operable rod rotatably connected to said block and extending rotatably and slidably through the angular portion of said one leg and the brace of the bracket, said rod constituting means for clamping the flexible jaw on the jar, and coacting means on the rod and the bracket for releasably securing the flexible jaw in clamping position.

PETER STELLINGWERF.
